UNITED STATES PATENT OFFICE.

WILLIAM G. KENDALL, OF NEWARK, NEW JERSEY.

PARTITION FOR VANITY CASES.

Application filed October 14, 1920. Serial No. 416,848.

To all whom it may concern:

Be it known that I, WILLIAM G. KENDALL, a citizen of the United States, residing at Newark, in the county of Essex and State of New Jersey, have invented certain new and useful Improvements in Partitions for Vanity Cases, of which the following is a specification.

This invention relates to improvements in vanity cases and more particularly to an improved partition for a case of that type which is designed to contain two compressed powder pads.

One of the objects of the invention is to provide a partition which may be readily formed from a sheet metal blank and which will be inexpensive to manufacture and substantial and durable.

Another object of the invention is to provide a partition member which will be inconspicuous and which yet will be adapted to effectually perform its functions of dividing the interior of the body of the vanity case into two compartments to individually receive the compressed powder pads.

In the accompanying drawing:

Figure 1 is a perspective view of a vanity case equipped with the partition embodying the invention;

Figure 2 is a vertical longitudinal sectional view through the body of the case and the partition disposed therein;

Figure 3 is a perspective view of the partition removed from the case.

In the drawings the body of the case is indicated in general by the numeral 1 and the usual hinged lid by the numeral 2, these parts being of the ordinary well-known construction. The numeral 3 indicates the compressed powder pads which are to be retained within the case within the compartments afforded by the disposal of the partition within the body of the case, the partition being indicated in general by the numeral 4.

The partition embodying the invention comprises two side members which are indicated by the numeral 5 and which are of arcuate form, the members having their con-

vex sides disposed in opposing relation so that their concaved sides will be adapted to receive or embrace or partially circumscribe the adjacent sides of the compressed powder pads 3 between which the partition is arranged within the body of the vanity case. 55 The side members 5 of the partition are connected at their lower edges by an integral web portion which is indicated by the numeral 6 and which may extend throughout any desired portion of the length of the members 5 in order to suitably connect and relatively brace the members. The web 6 is flat and preferably occupies substantially the same plane as that occupied by the lower edges of the said side members 5 so that it, 65 together with the said edges, will rest upon the upper face of the bottom of the body of the vanity case when the partition is disposed within the said body in the position shown in Figures 1 and 2 of the drawings. 70 When the partition member is so disposed within the case, the extremities of its side members 5 will engage against the front and rear walls of the said body of the case and thus the partition will be retained against 75 displacement.

Having thus described the invention, what is claimed as new is:

1. A partition for vanity cases and the like comprising side members formed to embrace articles to be retained within the case, and a web connecting the said side members. 80

2. A partition for vanity cases and the like comprising side members formed to embrace articles to be retained within the case, 85 and a web integrally connecting the lower edges of the said side members.

3. A partition for vanity cases and the like comprising arcuate side members having their convex sides presented in opposition to each other and their concave sides presented outwardly in opposite direction to embrace articles to be retained within the case, and a web connecting the said side members substantially in the plane of their 90 lower edges.

In testimony whereof I affix my signature.
WILLIAM G. KENDALL. [L.S.]
